Howson & Howson.

UNITED STATES PATENT OFFICE.

GUSTAVE KOEHLER, OF PHILADELPHIA, PENNSYLVANIA.

TILE CUTTER.

Application filed March 3, 1926. Serial No. 92,021.

My invention relates to tile cutters, and particularly to a tool of this class which is adapted to be rigidly secured to the tile setter's mortar board for convenience, and 5 comprises a simple and efficient means for scoring the glazed surface of tile units such as those used in bathrooms and like places.

Other advantages and the details of the invention will be more fully described here- 10 inafter being clearly illustrated in the accompanying drawing, of which:

Figure 1 is a side elevation of my improved tile cutter;

Fig. 2 is a plan view;

Fig. 3 is a transverse sectional elevation taken along the line 3—3 of Fig. 1, and

Figs. 4 and 5 are respectively a plan and transverse sectional elevation of a modification of one of the details of my invention.

As illustrated in Figs. 1, 2 and 3 of the drawing, my invention comprises a rigid frame consisting of a substantially horizontal bar 1 having at one of its ends a downwardly extending point 2 by means of which 25 the frame is adapted to be secured to a tile setter's mortar board 3, or to some other relatively substantial structure. In some instances the bar 1 may be provided with feet at each of its ends, for the purpose of permanent attachment to a supporting structure.

Adjustably secured to the frame 1 is an abutment gage 4 provided with downwardly extending lugs 5, 5 which project on either 35 side of the main bar of the frame 1. A clamp bolt 6 is provided and passes through apertures formed in the lugs 5, 5 at a point immediately underlying the main horizontal bar of the frame 1. Upon turning the bolt 40 6, the lugs 5, 5 are drawn into contact with the frame 1, thereby rigidly securing the gage 4 to said frame. The gage 4 also comprises a transversely extending bar 7 which forms a rigid abutment for a tile, X, during 45 the process of scoring.

The bar 7 is provided with an adjustable limit stop 8 having lugs 9, 9 adapted to embrace the bar 7 on its upper and lower surfaces, and being provided with a clamp 50 screw 10 which passes through the upper lug 9 and is threaded into a correspondingly tapped aperture in the lower lug 9, by means of which the limit stop 8 may be rigidly secured in an adjusted position upon the bar 55 7. The bar 7 is provided with measurement graduations illustrated at 11, Fig. 2, by

which the position of the limit stop on the transverse bar may be gaged.

The scoring of the tile X is accomplished by means of a bevelled rotary scoring or cutting tool 12 which is rotatably mounted in the forked end 13 of a horizontally extending bar 14. The cutter bar 14 extends in a plane substantially parallel to the horizontal element of the frame 1, and is supported upon the frame 1 adjacent the end opposite the rotary cutter by means of a roller bearing, comprising a flanged roller 15.

The end of the cutter bar 14, opposite the scoring tool 12, is pivotally attached at 16 to a lever 17, by means of which the scoring tool is traversed across the tile X. The lever 17 is provided at one end with a handle and its opposite end is pivotally secured at 18 to a link 19, the opposite end of which is pivoted at 20 to the frame 1.

Upon reference to Fig. 2, it will be apparent that the lever 17, in the present instance, is formed from a continuous piece of strap metal projecting downwardly at each side of the cutter bar 14 and the frame 1; and the link 19 is duplicated at each side of the frame 1 in the manner illustrated, a filling washer 21 being provided at the pivot 18 for the purpose of acquiring stability at said pivot.

In order to effect the proper scoring or cutting of the glazed face of a tile, it is necessary to apply pressure to the rotary tool 12, and for this purpose the frame 1 is provided with a vertical extension 25 which comprises a U-shaped strap extending below the frame 1 and upwards on each side thereof, as illustrated in Fig. 3, being secured to the frame by means of rivets 26, in the present instance.

Intermediate the upper ends of the extension 25, I provide a threaded block 27, secured to the strap members of the projection 25 by means of rivets 28, and having a threaded aperture adapted to receive an adjusting screw 29, which is provided at its upper end with a knurled head 30 by means of which the screw 29 may be turned within the block 27.

A shoe 31 is provided adjacent the upper surface of the cutter bar 14, and has ears 32 extending at each side of the projection 25, by which the shoe 31 is maintained within the slot formed in said projection and is permitted vertical movement therein.

Within the shoe 31, I provide a compressible element comprising a block of rubber 33 in the present instance, and upon the upper surface of the pad 33 I provide a plate 34 having downwardly extending flanges 35 which engage the rubber block at each end thereof and secure the plate 34 in position thereon. It will be understood that a spring may be used in place of the rubber pad 33 for the purpose of applying pressure to the cutter bar 14. The screw 29 is adapted to engage the plate 34, as shown in Figs. 1 and 3, for the purpose of controlling the amount of pressure applied to the cutter bar 14. In operation, where it is desired to cut tile for various reasons and purposes, the tile setter may adjust the gage limit stop 8 upon the bar 7 to the reading thereon, corresponding to the amount he desires to remove from the individual tile, whereupon the gage limit stop 8 is secured in position by turning the screw 10.

The rotary scoring or cutting tool 12 normally occupies the position illustrated in broken lines in Fig. 1, and the tile setter places the tile to be cut between the horizontal bar of the frame 1 and the cutter bar 14, against the abutment bar 7 and the gage limit stop 8, the tile resting upon the upper surface of the frame 1, the rear end of the cutter bar 14 being movably supported upon the roller 15 as clearly illustrated in said figure.

By turning the screw 29, the operator may minutely control the amount of pressure applied to the tool 12 through the medium of the compressible element 33. Upon moving the handle 17 in the direction of the arrow, Fig. 1, the tool 12 is passed over the glazed surface of the tile, as clearly illustrated in the drawings and thereby scores or cuts the said glazed surface in a manner as illustrated at Y in Fig. 2.

After passing the tool 12 completely across the tile X, the said tool rests upon the upper surface of the abutment gage 4, whereafter the tile setter may remove the scored tile and upon tapping the tile on its reverse surface the said tile will be broken along the scored line Y, the adjacent broken edges of the tile pieces presenting a comparatively smooth surface substantially perpendicular to the glazed face of the tile and requiring very little or none of the customary stone dressing usually required in order to permit the tile to be set in place.

In Figs. 4 and 5, I have illustrated an abutment gage which may be adjusted around a definite center in a horizontal plane for the purpose of cutting the tile on any angle desired, and to accomplish this purpose the frame 1 is composed of parallel bars 1^a which provide a slot 35 therebetween, adapted to receive a pivot bolt 36 integral

with the bar 7^a. Said bolt 36 extends downward from the upper surface of the bar 1^a through a lock plate 37 and is provided at its lower end with a winged nut 38, by means of which the gage bar 7^a may be rigidly secured in its adjusted position upon the upper surface of the bars 1^a.

Various modifications may be made to the details of my invention without departing from the essential features thereof, and only such limitations should be placed thereon as are prescribed in the appended claims or as may be imposed by the prior art of record. The drawing should in no way be construed as limiting the invention, being an illustration of the preferred form only.

I claim:

1. A tile cutter comprising a frame for supporting a tile in correct position to be cut; an adjustable abutment gage for said tile; a rotary cutting tool adapted to be traversed across, and in engagement with, the face of the tile; a cutter bar for carrying said cutter; a roller bearing for said bar, loosely mounted intermediate said bar and said frame being capable of free movement longitudinally of said frame and said cutter bar; means for applying pressure to the cutter bar intermediate said cutter and said roller bearing; and means for moving the cutter across the tile.

2. A tile cutter comprising a frame for supporting a tile in correct position to be cut; an adjustable abutment gage for the tile; a rotary cutting tool adapted to be traversed across, and in engagement with, the face of the tile; a cutter bar for carrying said cutter; a roller bearing for said cutter bar intermediate the bar and the frame; means for applying pressure to the cutter bar; a lever pivoted to said bar, for moving the cutter across the tile; and a link pivoted to said lever and said frame for permitting a substantially parallel movement of the cutter bar with respect to the frame.

3. A tile cutter comprising a frame for supporting a tile in correct position to be cut; a vertical projection on said frame; an abutment on the frame for the tile; a cutting tool adapted to be traversed across, and in engagement with, the face of the tile; a cutter bar for carrying said cutter; a flanged roller, intermediate the bar and the frame; means for applying pressure to the cutter bar comprising a shoe adapted to ride said cutter bar within said vertical projection; a compressible element on said shoe; a plate on said compressible element; adjusting means in said vertical projection adapted to engage said plate; and means for moving the cutter across the tile.

GUSTAVE KOEHLER.
